UNITED STATES PATENT OFFICE.

ANDREW F. CURTIN, OF MEDFORD, MASSACHUSETTS.

DESIGN FOR A WATER-CLOSET TANK.

52,524.

Specification for Design.

Patented Oct. 8, 1918.

Application filed January 5, 1918. Serial No. 210,573. Term of patent 14 years.

To all whom it may concern:

Be it known that I, ANDREW F. CURTIN, a citizen of the United States, residing at Medford, in the county of Middlesex and Commonwealth of Massachusetts, have invented a new, original, and ornamental Design for a Water-Closet Tank, of which the following is a specification, reference being had to

the accompanying drawing, forming a part thereof.

Figure 1 is a perspective view, and Fig. 2 is a front elevation of the tank.

I claim:—

The design for a water-closet tank substantially as shown.

ANDREW F. CURTIN.
